UNITED STATES PATENT OFFICE.

JOHN H. BRUNINGA, OF ST. LOUIS, MISSOURI, ASSIGNOR TO STANDARD HEEL & COUNTER CO., OF ST. LOUIS, MISSOURI, A CORPORATION OF MISSOURI.

FLOOR MAT.

Application filed November 17, 1921. Serial No. 515,825.

To all whom it may concern:

Be it known that I, JOHN H. BRUNINGA, a citizen of the United States, and residing at St. Louis, Missouri, have invented the new and useful Improvement in Floor Mats, of which the following is a specification.

This invention relates to floor mats, and more particularly to such mats as are constructed of a series of links of leather or the like connected together by hinged joints to facilitate the rolling up of the mat when not in use.

One of the great difficulties encountered in the use of mats of this kind is their tendency, after having been in use for a short time, to curl up at the edges, as the leather is soft and pliable and is, therefore, subject to twisting and curling. This makes the edge stand up away from the floor in a position where it may easily be struck by the foot in passing, with danger of tripping and consequent personal injury.

One of the objects of this invention, therefore, is to provide a mat of the character referred to, whose edge will be constructed and arranged to lie flat on the floor and to prevent curling.

Further objects will appear from the detail description taken in connection with the accompanying drawing, in which:

Figure 1 is a plan view showing a mat embodying this invention;

Figure 2 is a detail of a short link;

Figure 3 is a similar detail of a long link; and

Figure 4 is a view showing the relative positions of the long and short links at the edge of the mat.

Referring to the accompanying drawing, the mat is built up of a series of short links 5 of normal length which, in this description, will be called a short link. These links comprise each a series of laminas 1 of leather or the like, which are punched out of leather to the form shown in Figure 2, scraps of leather resulting from the manufacture of other leather articles often being used for this purpose. Each lamina is provided with holes 2 near the ends thereof, and the laminas are assembled together to form a series of links arranged in rows, with the links of adjoining rows alternating, by passing pintle rods through the holes 2 to connect the various links together. The links

may be arranged in a chain pattern as illustrated in Figure 1, so as to form a flexible chain like structure. The pintle rods may be constructed of stout wires 3 bent into substantially a U form, each wire U being passed through two holes in the adjacent sections of links and the ends of the wires may be turned over as shown at 4 and soldered, or otherwise fastened together.

As will be seen from Figure 1 the mat is made up of successive rows of groups of lamina, each group 5 being composed of a plurality of individual lamina 1 placed side by side. With such an arrangement thin lamina can be used, but a substantial bearing surface is provided which will not break down, especially since the pintle rods, which are clenched over at their ends, hold all the links and the laminas thereof together to form a compact but flexible chain-like structure. Each of these rows of links forms a mat section extending across the mat and having a hinge at each edge thereof at the pintle rods 3. By this arrangement the mat may be rolled, the sections bending at the hinges during the process.

The end section of the mat may be composed of alternate groups or links 6 and 7 made up respectively of long laminas 8 formed as shown in Figure 3 and also of leather or the like, and short laminas 1. The long laminas engage the pintle rod 3 of the adjacent mat section, being thereby hinged thereto in the manner just described. The groups 7 are interposed between the ends of the groups 6 and one of the U-wires 9 is passed through the entire assemblage. There is thus formed a solid end section for the mat made up as described of alternate groups 6 and 7 of long and short laminas respectively, which presents a continuous edge along the end of the mat. This end section is stiff having no hinge except where the long links join the succeeding row of short links. In other words, the wires 9 are not pintle rods but simply hold the links of the end section together. This end section will lie flat on the floor when the mat is extended and there will be no tendency for it to curl up as is the case when the end section of a mat has a hinge close to the end of the mat.

When it is desired to stiffen the mat at an intermediate section, this may be done

by the use of the long links or laminas 8 as indicated in the lower part of Figure 1, where a section is formed of alternate groups 6 and 10, each composed of a number of long laminas 8, but faced in opposite directions and each being hinged to an adjacent section of short laminas 1.

It will, therefore, be seen that the invention accomplishes its objects. A mat is provided which will lie flat when in use and this result is obtained by providing a series of links 6 adapted to stiffen the edge of a mat so as to prevent its turning up. These links together with the series 7 of short links provide a stiff unhinged end section which will lie flat by its own weight. The provision of such a stiff end section at the same time would not interfere in any way with the rolling up of the mat when desired.

It is obvious that various changes may be made in details of construction without departing from the spirit of this invention; it is, therefore, to be understood that this invention is not to be limited to the specific details shown and described.

Having thus described the invention, what is claimed is:

1. A flexible floor mat comprising, a series of short leather links, arranged in rows with the links of adjoining rows alternating, a series of pintle rods joining said links to form a flexible chain-like structure, the links of an inside-row being extended so as to receive the pintle rods of the end row, adapted and in order to stiffen and retain the edge of the mat flat when extended.
2. A flexible floor mat comprising, a series of short leather links of normal length, arranged in rows with the links of adjoining rows alternating, a series of pintle rods joining said links to form a flexible chain-like structure, and links of double length embracing the end row and the adjoining inside

row, adapted and in order to stiffen and retain the edge of the mat flat when extended. 45

3. A flexible floor mat comprising, a series of short leather links arranged in rows with the links of adjoining rows alternating, a series of pintle rods joining said links to form a flexible chain-like structure, the links 50 of an inside row being extended so as to embrace rows on opposite sides thereof, substantially as and for the purpose set forth.

4. A flexible floor mat comprising, a series of short leather links of normal length, arranged in rows with the links of adjoining rows alternating, a series of pintle rods joining said links to form a flexible chain-like structure, and links of double length in an inside row and extending on opposite sides 60 thereof, substantially as and for the purpose set forth.

5. A flexible floor mat comprising, a series of short links, each embodying a series of leather laminas arranged in rows with the links of adjoining rows alternating, a series of pintle rods joining said links to form a flexible chain-like structure, the links of a certain row being extended so as to receive the pintle rods of the joining row, substantially as and for the purpose set forth. 70

6. A flexible floor mat comprising, a series of short links of normal length and a series of links of double length, each link embodying a series of leather laminas the links of normal length being arranged in rows with the links of adjoining rows alternating, the links of double length being arranged in a row and embracing an adjoining row, and a series of pintle rods joining said links to form a flexible chain-like structure, substantially as and for the purpose set forth. 75 80

In testimony whereof I affix my signature this 30th day of September, 1921.

JOHN H. BRUNINGA.
